UNITED STATES PATENT OFFICE.

ALBIN CARLSON, OF MINNEAPOLIS, MINNESOTA, ASSIGNOR TO STANDARD ENGRAVING AND CUT GLASS COMPANY, OF MINNEAPOLIS, MINNESOTA, A CORPORATION OF MINNESOTA.

DESIGN FOR A CUT-GLASS VESSEL.

43,267.

Specification for Design.

Patented Nov. 26, 1912.

Application filed September 16, 1912. Serial No. 720,701. Term of patent 7 years.

To all whom it may concern:

Be it known that I, ALBIN CARLSON, a citizen of the United States, residing at Minneapolis, in the county of Hennepin and State of Minnesota, have invented a new, original, and ornamental Design for a Cut-Glass Vessel, of which the following is a specification, reference being had to the accompanying drawing, forming part thereof.

Figures 1 and 2 are elevations showing

opposite sides of a vase having cut thereon my design.

I claim:

The ornamental design for a cut glass vessel, as shown.

ALBIN CARLSON.

In the presence of—

EDITH HANNA,

HARRY D. KILGORE.
